UNITED STATES PATENT OFFICE.

THOMAS W. JENKS, OF AVALON, PENNSYLVANIA.

METHOD OF ROLLING RIBBED BARS.

No. 882,321.

Specification of Letters Patent. Patented March 17, 1908.

Application filed April 2, 1907. Serial No. 365,931.

To all whom it may concern:

Be it known that I, THOMAS W. JENKS, of Avalon, Allegheny county, Pennsylvania, have invented a new and useful Method of Rolling Ribbed Bars; of which the following is a full, clear, and exact description, reference being had to the accompanying drawings, forming part of this specification, in which—

Figures 1, 2 and 3 are views illustrating the three successive passes used in my method of rolling ribbed bars; Figs. 1^a, 2^a and 3^a are perspective views showing portions of the bars, as they leave the respective passes of Figs. 1, 2 and 3. Fig. 4 is a cross-section of the finished bar.

My invention has relation to a novel method of forming metal bars for use in concrete reinforcement, and more particularly to a method of rolling bars having two or more continuous longitudinal ribs or projections, with bracing ribs or projections connecting the longitudinal ribs or projections and forming a series of pockets or depressions for bonding the concrete to the bar.

Prior to my invention it has not been considered practicable or possible to roll a bar of this form, owing to the difficulty of forming the continuous longitudinally-extending ribs or projections and the cross or connecting projections; and my invention consists in the method whereby this object is successfully and commercially accomplished.

In accordance with my invention, I take a billet of approximately rectangular cross section and pass it through a pair of rolls having a pass such as shown in Fig. 1, which receives the billet in a diagonal position. This pass has a horizontal dimension greater than its vertical dimension, so that the billet as it passes therethrough is somewhat flattened into a cross section of diamond or lozenge form, as shown in Fig. 2^a, the opposite horizontal angles or corners being by the same operation provided with continuous longitudinally-extending ribs or projections 2, as shown in Fig. 2^a, due to the lateral flow of the metal.

The bar or blank is next entered into a roll pass having the form shown at 3 in Fig. 2, and in which the vertical axis or dimension of the blank is further reduced, and its horizontal axis or dimension is increased, the longitudinal ribs or projections 2 being further extended and developed. This pass is also provided with the roll grooves 4 which form corresponding ribs or projections 5 at

the upper and lower corners of the bar, as shown in Figs. 2 and 2^a.

The bar is next entered into the third and finishing pass, shown in Fig. 3, being introduced in this pass with its greatest dimension extending vertically. This pass which is shown at 6 in Fig. 3 is of approximately rectangular cross-section. The pass-forming groove in each roll is of V form with circumferential grooves 7 at its bottom similar to the groove 4 of Fig. 2, and both sides of the pass are formed with the cross grooves 8 which extend into the circumferential groove. In this pass, the previously-formed ribs or projections 2 engage the circumferential grooves 7, and the vertical axis is reduced, while the horizontal axis is increased, the excess of metal provided by the reduction of the vertical axis being forced outwardly into and filling the cross grooves 8 of the pass, to thereby form the bracing ribs 9 of Figs. 3^a and 4. In this final pass, the longitudinally-extending ribs or projections 2 are finished by the circumferential grooves 7 of the pass, while the other two ribs or projections 5 are finished by the lateral flow of the metal between the joints of the rolls.

The advantages of my invention result from the fact that by the method described I provide in the first and second passes such a disposition of the metal in the blank that in the final or finishing pass an excess is provided which is caused by the vertical pressure of the rolls to flow laterally into and completely fill the cross grooves, to thereby form the connecting ribs. That is to say, instead of rolling depressions in the surfaces of the blank, I positively force the metal outward and laterally to form these ribs. In this manner, I am able to preserve the continuity of the longitudinally-extending ribs or flanges without weakening them at any point, while the arrangement and disposition of the bracing ribs is such as to provide a bar having a strength substantially equal to its maximum cross-section, while there is effected a saving of approximately 20 per cent. in metal with the provision of the bonding recesses. These recesses provide a perfect and mechanical bond for uniting the concrete to the bar.

While I have shown and described my improved method in connection with the formation of a finished bar having an approximately rectangular shape, it will be obvious

that the invention is not limited thereto, but that the bar may be of any desired cross section.

What I claim is:—

5 1. The herein described method of rolling ribbed bars which consists in forming a blank of diamond or lozenge shape in cross-section with a continuous rib or projection at each of its angles, and having one of its axes or

10 dimensions greater than the other, and then rolling said blank between die rolls to effect a reduction in which its axes are approximately equalized, and the excess of metal is caused to flow laterally to form ribs or projections at substantially right angles to the first-named ribs or projections; substantially as described.

2. The method of shaping metal bars, which consists in rolling a blank of lozenge or 20 diamond shape in cross-section to increase one of its dimensions and reduce its other dimension, and causing the excess of metal to flow laterally into cross-grooves which are in the walls forming the passes of the rolls so as 25 to form ribs or projections extending approximately at right angles to the longitudinal axis of the bar; substantially as described.

3. The method of forming metal bars having longitudinally-extending ribs or projections at its angles, and other ribs or projections connecting the same at approximately right angles, which consists in forming a blank or shape of diamond or lozenge form in cross-section, with one of its cross axes or dimensions greater than the other, and having a continuous longitudinally-extending rib or projection at each of its angles, and then rolling said shape between die rolls to approximately equalize its two 40 axes or dimensions, and force the excess of metal laterally outward between the longitudinal projections at recurring intervals in the form of connecting ribs; substantially as described.

45 4. The method of forming metal bars having transversely ribbed surfaces, which con-

sists in rolling a blank of diamond shape in cross-section to reduce one of its cross axes and to increase the other one, but to a lesser extent than the decrease of the first-named 50 axis, and at the same time forcing the excess metal to flow laterally outward in cross grooves in the walls of the roll passes so as to form successive spaced ribs; substantially as described.

5. The method of rolling ribbed bars, consisting in forming a blank of substantial lozenge shape with at least two longitudinal ribs at its corners or angles, and having one axis greater than the other, and then reducing one of its axes and increasing the length of the other between rolls having grooved portions in the walls, which form the sides of the roll passes, and thereby forming cross-ribs or projections thereon in said pass; substantially as described.

6. The method of forming a bar having a body portion and projecting portions integral therewith, which consists in utilizing a blank having a cross-axis longer than the corresponding axis of the bar to be formed therefrom, and a second cross-axis which is substantially at right angles to the first mentioned cross-axis of a length which is less than the corresponding cross-axis through 70 the body and projecting portions of the aforesaid bar, subjecting the said blank to the action of rolls, having grooved passes between them and recessed portions in the walls which form the sides of the roll passes, in 80 such a way that the cross-axis of the said blank is reduced while the length of its second cross axis is increased and simultaneously therewith the metal is forced laterally into the said recessed portions; substantially 85 as described.

In testimony whereof, I have hereunto set my hand

THOMAS W. JENKS.
